DESIGN FOR A MEMORIAL PLAQUE OR SIMILAR ARTICLE

David Bank, Minneapolis, Minn.

Application July 30, 1934, Serial No. 52,734

Term of patent 14 years

To all whom it may concern:

Be it known that I, David Bank, a citizen of the United States, residing at Minneapolis, in the county of Hennepin and State of Minnesota, have invented a new, original, and ornamental Design for a Memorial Plaque or Similar Article, of which the following is a specification, reference being had to the accompanying drawing, forming part thereof.

The figure is a plan view of a convex memorial plaque having no appreciable thickness, showing my design which resides in the shepherd with a halo over head, holding a crook in one hand and shielding a sheep with the other hand; two candles are set in holly trim. the church window forms the background, an open space for the name to be engraved, and the words "In Memory" on background.

I claim:

The ornamental design for a memorial plaque, or similar article, as shown and described.

DAVID BANK.
